HAT

Barbara L. Goldfarb, 30165 Stellamar Drive,
Birmingham, Mich. 48010

Filed May 25, 1970, Ser. No. 23,120

Term of patent 14 years

Int. Cl. D2—03

U.S. Cl. D2—239

FIG. 2

FIG. 3

FIG. 1

FIG. 4

FIG. 1 is a front perspective view of a hat showing my new design.

FIG. 2 is a front elevational view thereof.

FIG. 3 is a right side elevational view thereof, the left side being a mirror image thereof.

FIG. 4 is a rear elevational view thereof.

I claim:

The ornamental design for a hat, substantially as shown and described.
